STEEL SHEET-PILING.

1,005,514.

Specification of Letters Patent. Patented Oct. 10, 1911.

Application filed February 20, 1911. Serial No. 609,640.

To all whom it may concern:

Be it known that I, CLOUD CLIFFORD CONKLING, a citizen of the United States, residing at Buffalo, in the county of Erie and State of New York, have invented new and useful Improvements in Steel Sheet-Piling, of which the following is a specification.

My invention relates to steel sheet piling in which the wall of piling is formed of 10 separate, rolled, integral, steel sections having interlocking members along both edges, adapted to interlock or engage with similar members on adjacent sections, and consists in a new construction of a pile section, 15 having certain important advantages.

My new section belongs to the class first described by Hill in Patent No. 829,399 in which the section edge is provided with an inner hook member and an outer guard 20 member, and to the particular variety of that class known as the "flexible joint", whereby sufficient angular and longitudinal adjustment between the adjacent sections is permitted.

My pile section is superior to any others with which I am acquainted, in the strength 25 of the interlock, and in its high moment of inertia, and consequent great lateral strength as a vertical beam when driven to final working position. It has also preserved one desirable feature of the Hill form, that is the arrangement of the hooks with their engaging faces at right angles to the longitudinal stress, thus opposing the greatest resistance 30 to that stress, and preventing the said faces from sliding on one another when under pressure. But in the Hill form this feature is combined with the "rigid joint", whereas in my present invention it is combined with 35 the "flexible joint". Another characteristic and important feature is the guard members, so formed and arranged as to resist a large part of the longitudinal stress, as well as to prevent lateral displacement, thereby 40 greatly increasing the strength of the interlock; this strength is not greatly affected by turning the sections at such different angles, one to the other, as ordinarily required in sheet pile constructions, but is 45 practically the same for all such different positions of angular adjustment. By my invention all these advantages are combined in a form of pile section permitting sufficient angular and longitudinal adjustment 50 and providing sufficient clearance between 55

the outer surfaces of the hooks and the inner surfaces of the guards to make the driving easy and to form the necessary pockets for packing, thus adding to the water-tight qualities of the joints.

My invention and the particular form of pile involving my invention which is here shown will be understood by reference to the drawing herewith in which the reference numerals and letters of this description indicate the corresponding parts in all the figures.

Figure 1 is a fragmentary isometric view showing the pile sections assembled in a wall. Fig. 2 shows the same in plan. Fig. 3 is a plan illustrating the angular adjustment of the pile section. Fig. 4 shows in plan a single pile of modified form. In Figs. 1 and 2 the piles are shown in normal position, that is with uniform clearance at all points between the contact surfaces, being the position of the piling on which the length of the wall is calculated; in Fig. 3 the surfaces are shown in full contact, in which position the space occupied by each pile in the wall is increased.

Each pile section consists of the web A having on each edge the hook member B and the longer guard member C. Those members are arranged to form the groove D, sufficiently large freely to receive the hook member of the adjacent pile and to permit sufficient, but not excessive, longitudinal and lateral movement of the hook in the groove and therefore free driving, and also facilitating the final closure of the construction. The hook member consists of an elbow 1 offset on one side of the web with its outer surface 2 formed in a simple curve. From the elbow extends, substantially, or almost, parallel to the web, the hook-shank 3, carrying at its outer end the hook or tip 4 whose engaging surface 5 is substantially at a right angle to the plane of the web and is preferably short. The inner surfaces of the shanks 100 are in fact substantially parallel to the web, but it will be seen that the outer surfaces incline outwardly a little; this is for the reason that the hook member must be stronger and therefore heavier toward the end. On the other side of the web extends the guard shank 6 preferably inclined outwardly at a small angle to the web and having on its outer end the laterally extending finger 7 whose inner surface 8 is a simple curve sub- 110

stantially concentric with the curve of the elbow. These curves are rather flat, and approximate lines drawn at a right angle to the plane of the web. There are thus three lines of engagement at each interlock, the two hook faces, and the fingers with the two elbows. As the hook faces are short and the curves of the fingers and of the elbows centered thereon, the piles are free to turn one on the other, that is angularly to adjust themselves, during driving as is best shown in Fig. 3. In all these varying angular positions the hook faces, or inner engaging surfaces, remain in substantially the same position, that is at a right angle to the longitudinal stress, whereby the greatest resistance to the stress is obtained and tendency to slip one on the other is avoided. In case of angular adjustment, the concentric finger and elbow, or outer engaging surfaces, turn on those hook faces as centers, and the lines of stress are in all positions radial, that is substantially at right angles, to these outer surfaces. As the degree of angular adjustment changes, the engagement of one outer bearing shortens, but the other correspondingly increases, so that the strength of the interlock is the same in all positions. To be strictly accurate it should be stated that at the maximum angle of angular adjustment of about twelve degrees indicated at the left in Fig. 3, there will be more leverage tending to bend the fingers, and therefore the interlock in that position will be slightly weaker, but it will be understood that in most installations requiring heavy piling of this type, this maximum angle is seldom reached, or approached, but an angle of one to four degrees is usually sufficient for all purposes, and at such a small angle there is no practical decrease in strength. In all of the varying angular positions there is sufficient clearance for free driving, and the sealing pockets 9-9 are of sufficient size to admit the material displaced in driving, and pack it in the said pockets, whereby the water tightness is increased. The packing is commonly the soil in which the piles are driven, but other material might be inserted from above. Flexible joints, permitting sufficient angular and longitudinal adjustment, are necessary for most installations. The angular adjustability is necessary to maintain the general line of the wall while permitting local curving thereof in order to circumnavigate obstacles met in driving the sections. The longitudinal adjustment is necessary to permit the wall to be lengthened or shortened, by expanding or shortening at the joints, to allow the final closure of the wall or walls, as in coffer-dam pockets. Rigid joint piling permits neither longitudinal nor angular adjustment, and furthermore is liable to produce leverage within the joints when driving, should the piles tend to de-

part from a straight line, thereby weakening the joints.

To increase the strength of the interlock in pile sections, necessarily the amount of metal in the interlocking members must be increased. The metal in my present form is so arranged on both sides of the neutral axis, as to produce a joint with a high moment of resistance in the section, and increased lateral strength, giving greatly increased strength in the pile when in final position it acts as a vertical beam. The interlock is also stronger than that of any piling with which I am acquainted, and may be proportioned to be equal to the strength of the web, producing a wall of practically uniform strength at all points. The parts are so formed that there will be sufficient clearance for easy driving, and sealing pockets of sufficient size to receive the displaced material or packing, thereby adding to easy driving and increased water-tightness of the joints. The metal is symmetrically arranged around the transverse axes, which arrangement is desirable for correct driving because the center of gravity of the section more nearly coincides with the center of gravity of the pile hammer. An excess of metal on one side or the other of the transverse axis would tend to force the top of the section ahead or back in driving.

The particular form of section herein shown may be somewhat modified without departing from the spirit of my invention, of which some features may be used with other types of piling.

Having thus described my invention, I claim,

1. An integral sheet piling section having a web and on each edge thereof interlocking elements consisting of a hook and a guard, said guard being longer than the hook and being adapted to extend around and engage with the outer surface of the hook on an adjacent section when assembled in a wall, and said hook having an engaging face practically at a right angle to the plane of the web.

2. An integral sheet piling section having a web and on each edge thereof interlocking elements consisting of a hook and a guard, said elements each having a substantially straight shank, said hook having an engaging face to engage with a hook on an adjacent section, and said guard being longer than the hook and being adapted to extend around and engage with the outer surface of said hook on the adjacent section.

3. An integral, rolled, steel sheet piling section of the flexible joint type having a web and on each edge thereof interlocking elements consisting of a hook and a guard, said elements each having a substantially straight shank, the hook having an engaging face arranged at a right angle with the

- plane of the web to engage with a corresponding face on the hook of an adjacent section, and the guard being longer than the hook and being adapted to extend around and engage with said hook on the adjacent section.
4. A steel sheet piling section for interlocking steel piling having a web and on each edge thereof a hook and a guard, both provided with substantially straight shanks and inwardly extending ends on the shanks, and the guard being longer than the hook.
5. An integral steel sheet piling section of the flexible joint type, having a web and on each edge thereof, a hook and a guard inclosing a groove of sufficient size freely to receive the hook on an adjacent section and to leave a sealing pocket within the groove, said hook having a tip provided with an engaging face arranged substantially at a right angle to the web.
6. An integral, steel, sheet piling section of the flexible joint type, having a web and on each edge thereof a hook and a guard inclosing a groove of sufficient size freely to receive the hook on an adjacent section and to leave a sealing pocket within the groove, said hook having a tip provided with an engaging face arranged substantially at a right angle to the web, and said guard being arranged to engage with the outer surface of said hook on the engaging section, the sections when assembled having three separate lines of engagement being between the hook faces, and between each guard and the outer surface of each hook.
7. An integral rolled steel sheet piling section of the flexible joint type, having in combination a web and on each edge thereof of a hook and a guard inclosing a groove of sufficient size freely to receive the hook on an adjacent section and to leave a sealing pocket within the groove, the hook consisting of an elbow offset on one side of the web, a shank and a tip on said shank having an engaging face arranged substantially at a right angle to the plane of the web, and said guard member having a finger engaging with said elbow.
8. An integral steel sheet piling section of the flexible joint type, having a web and on each edge thereof a hook and a guard inclosing a groove of sufficient size freely to receive the hook on an adjacent section and to leave a sealing pocket within the groove, said hook having a tip provided with an engaging face arranged substantially at a right angle to the web, the hook and guard each being provided with a shank offset from the plane of the web on opposite sides of the web and the guard having the longer shank, and each shank having an inwardly extending tip provided with an inner engaging surface.
9. An integral rolled steel sheet piling section of the flexible joint type, having in combination a web and each edge thereof similarly formed with a hook and a guard inclosing a groove of sufficient size freely to receive the hook on an adjacent section and to leave a sealing pocket within the groove, the hook consisting of an elbow offset on one side of the web, a shank and a tip on said shank having an engaging face arranged substantially at a right angle to the plane of the web, and the guard consisting of a shank offset on the opposite side of the web and of a tip having an inner engaging surface.
10. An integral, steel, sheet piling section having in combination a web and on each edge thereof a hook and a guard respectively offset on opposite sides of the web and said guard being longer than the hook, said hook having an elbow extending from the web, a shank on the elbow and an inwardly extending tip on the end of the shank, said elbow having an outer curved surface and said tip having a short, substantially straight, inner, engaging surface arranged substantially at a right angle to the web, and said guard having a shank and an inwardly extending finger on the shank end formed with a curved inner surface, and said curved surfaces on the elbow and the finger being flat curves approximating lines at a right angle to the web.
11. An integral, steel, sheet piling section having in combination a web and on each edge thereof a hook and a guard respectively offset on opposite sides of the web and said guard being longer than the hook, said hook having an elbow extending from the web, a shank on the elbow and an inwardly extending tip on the end of the shank, said elbow having an outer curved surface and said tip having a short, substantially straight inner engaging surface arranged substantially at a right angle to the web, and said guard having a shank and an inwardly extending finger on its end formed with a curved inner surface, said hook and guard inclosing a groove of sufficient size freely to receive the hook on an adjacent section and to leave a sealing pocket in the groove.
12. An integral, steel, sheet piling section of the flexible joint type, having in combination a web and on each edge thereof a hook and a guard respectively offset on opposite sides of the web and said guard being longer than the hook, said hook having an elbow extending from the web, a shank on the elbow substantially parallel to the web and an inwardly extending tip on the end of the shank, said elbow having an outer curved surface and said tip having a short, substantially straight, inner, engaging surface arranged substantially at a right angle to the web, and said guard having a

shank inclining away from the plane of the web and an inwardly extending finger on its end formed with a curved inner surface, said hook and guard inclosing a groove of sufficient size freely to receive the hook on an adjacent section, and to leave a sealing pocket in the groove, permitting angular adjustment of adjacent sections, and said curved surfaces on the hook

10 elbow and the guard finger being substan-

tially concentric and centered substantially on the short engaging faces of the hook tips.

In testimony whereof I have signed my name to this specification in the presence of 15 two subscribing witnesses.
